UNITED STATES PATENT OFFICE

STEPHEN JUNKUNC, JR., OF CHICAGO, ILLINOIS

DESIGN FOR A BURIAL CASKET

Application filed October 31, 1932. Serial No. 45,672. Term of patent 14 years.

To all whom it may concern:

Be it known that I, STEPHEN JUNKUNC, Jr., a citizen of the United States, residing at Chicago, in the county of Cook and State of Illinois, have invented a new, original, and ornamental Design for a Burial Casket, of which the following is a specification, reference being had to the accompanying drawing, forming part thereof.

I claim:

The ornamental design for a burial casket, as shown.

STEPHEN JUNKUNC, JR.
